UNITED STATES PATENT OFFICE.

HARRY E. TRAGER, OF ARCANUM, OHIO.

MIXER.

1,314,770.

Specification of Letters Patent. Patented Sept. 2, 1919.

Application filed April 5, 1917, Serial No. 160,059. Renewed February 1, 1919. Serial No. 274,570.

To all whom it may concern:

Be it known that I, HARRY E. TRAGER, a citizen of the United States, and resident of Arcanum, in the county of Darke and State 5 of Ohio, have invented certain new and useful Improvements in Mixers, of which the following is a specification.

This invention relates to charge forming devices and has more especial reference to 10 an improved suction control feed means for the device, whereby the supply of air and gas to the charge forming chamber thereof will be governed by the velocity at which the engine is operating.

15 It is the dominant object of the invention to provide a charge forming device employing natural or artificial gas having a novel form of air and fuel feeding means, the same being connected and operable synchronously by suction created by the engine 20 at times and by manual operable means at other times.

Another and equally important object of the invention is to arrange the air intake 25 means in a manner to permit independent adjustment of the same to regulate the inflow of air upon operation thereof by the engine suction.

It is also an object of the invention to 30 provide means for supplying and discharging the fuel in jet like form into the charge forming chamber of the device.

Other and further improvements and 35 novel details in the construction and arrangement of parts will be appreciated from the description to follow, which for a clear understanding of the invention should be considered in connection with the accompanying drawings forming a part hereof 40 and wherein the preferred embodiment of the invention is shown for the purpose of illustration.

In the drawings:

Figure 1 is a vertical longitudinal section 45 through the improved charge forming device;

Fig. 2 is a fragmental section showing the air intake cylinder in detail; and

Fig. 3 is a detail in bottom plan of the 50 air intake cylinder.

Similar characters of reference are employed in all of the above described views to indicate corresponding parts.

Referring now more specifically to the 55 several figures of the said drawings, there is provided a casing element designated 1,

the said casing being provided with intake and outlet or exhaust ports in the upper portion thereof axially of the casing and disposed in alinement, the usual butterfly 60 type of control valve designated 2 being arranged in the exhaust port and controlled from the seat of the vehicle or other structure in which the device is arranged.

A fuel supply conduit 3 located axially 65 of the casing 1 at one side is extended from a suitable gas reservoir to a point in proximity of the casing 1 and is provided with a downwardly curved branch discharge pipe 4, the outer extremity of which is reduced 70 and perforated as at 5 and is received through the lowermost part of the casing 1 adjacent to the wall thereof, the top or perforated side being flat as shown.

A cylindrical valve chamber 6 is secured 75 to the end wall of the casing 1 at a point adjacent the upper intake port by brazing or like processes and has formed in the bottom thereof a tapered slot or way 7 extending from a point spaced from the 80 outer or inlet end thereof and enlarging to its inner or discharge end. Loosely arranged about the cylindrical valve chamber 6 is a housing 8, which housing has its bottom portion provided with a correspondingly 85 positioned tapered slot or way 9, corresponding in size and shape to the way 7 formed in the said valve chamber 6. A lug 10 is fixedly secured to one side of the rotatable housing 8 and is engaged by a connection 11 90 which extends therefrom to a suitable point whereat the same may be conveniently operated.

Within the cylindrical valve chamber 6 a disk valve 12 is slidably mounted and is 9 engaged by one end of a connecting rod 13, the opposite extremity of the rod extending therefrom and adjustably connected with a gas supply control valve 14 which will be subsequently described. Obviously, movement of the slideable disk valve 12 over the tapered way 7 formed in the valve chamber 6 will serve as efficient means for controlling the passage of air therethrough into the casing or suction chamber 1.

To control the supply of gas to the discharge pipe 4, a solid cylindrical valve 14 is slidably positioned therein and is provided with a screw threaded opening in its outermost end whereby the complementally 1 threaded extremity of the connecting rod 13 may be turned into engagement therewith

and as a consequence, synchronous movement of the cylindrical valve 14 and the disk valve 12 thus caused the valves being also connected to be relatively adjusted. In this connection, it is to be noted that a depending lug 15 is formed upon the outer end of the cylindrical valve 14 in order that the same together with the disk valve 12 may be operated independently of the suction operation means, at times.

Upon the upper side of the supply conduit 3 there is arranged an apertured lug 16 having a tension screw 17 passing therethrough, the said tension screw being engaged with one end of a contractile coiled spring 18, the remaining end of which is secured to the connecting rod 13, thereby, serving as means for normally maintaining the several valves, namely, the valves 12 and 14 normally in closed position. By varying the positioning of the tension screw 17 with relation to the apertured lug 16, the tension of the coiled spring 18 may be varied and the movement of the valves 12 and 14 automatically controlled.

A lever 19 is pivotally secured to the discharge pipe 4 and has its upper end pivotally engaged with a slidable rod 20 passing through an apertured bearing 21 secured to the underside of the supply pipe 3. An operating connection 22 is engaged with the lower end of the lever 19 and upon rocking the said lever thereby will cause engagement of the rod 20 with the lug 15, hence, the movement of the valves 12 and 14 to open or partially open positions. By this means, priming of the engine is allowed in order that the same may be started.

In operation, the valves 12 and 14 are moved to positions to permit the flow of sufficient quantities of air and gas into the casing 1 to cause the priming of the engine in order that the same may be started. Upon operation of the engine pistons within their respective cylinders, a suction will be created in the intake manifold and as a consequence, in the casing 1. Such suction will act upon the disk valve 12 in a manner to cause the same to be moved inwardly with respect to its chamber 6, thereby varying the size of the way 7 formed in the bottom thereof and accordingly, the supply of air to the said casing. Simultaneous with the movement of the valve 12, the gas supply control valve 14 will be moved, thereby allowing a supply of gas to be shunted or fed into the discharge pipe 4 and from there introduced into the casing 1 whereat the same will be properly mixed with the inflowing air to form a highly combustive charge and then fed by way of the intake manifold into the various cylinders of the engine, the passage of the combustive charge through the intake manifold being of course controlled by the positioning of the butter-

fly valve 2. Should the speed of the engine be increased or decreased, the suction created thereby will accordingly be increased or decreased, and will cause the automatic adjusting of the valve 12 and consequently, the valve 14. Thus the supply of fuel to the engine cylinders is automatically controlled. To regulate the richness of the combustible charge, the casing 8 as rotatably mounted upon the cylindrical valve chamber 6 may be moved by means of the connection 11 operating in a slot 11' in the casing 1 to cause movement of the way 9 formed therein with relation of the way 7 formed in the valve chamber 6. It may be here noted, that the tapered formation of the ways 7 and 9 formed in the chamber 6 and casing 8 serve to allow the proper intake of air when the engine is running at high speed, since, the suction created by the engine will be greater and therefore will move the disk valve 12 inwardly to a greater extent.

Manifestly, the construction shown is capable of considerable modification and such modification as is within the scope of my claims, I consider within the spirit of my invention.

I claim:

1. In a carbureter, a charge forming chamber having intake and exhaust ports therein, a fuel supply means having a depending discharge nozzle extended into the charge forming chamber beneath said intake and exhaust ports, a valve chamber mounted within the charge forming chamber and coinciding with the intake port for the entrance of air, a sleeve rotatably mounted on said valve chamber and having a port formed therein complementary to the port formed in the valve chamber, a suction controlled valve slidable within the chamber, a valve slidable in the fuel supply means and connected to said suction controlled valve, adjustable resilient means connected with the suction controlled valve and normally holding the same and said second named valve in closed positions, said means being common to both valves, and means for causing synchronous operation of the valves to open the same against the action of said resilient means and independently of the suction operating means.

2. In a carbureter, a charge forming chamber having an intake and an outlet port therein disposed in alinement, a fuel supply conduit disposed in alinement with said ports, said conduit having a discharge nozzle leading into the chamber diametrically opposite to said ports, a valve chamber around the intake port, a suction controlled valve slidably arranged in the valve chamber, a valve slidable in the supply conduit and coöperating with the passage leading to the nozzle to regulate the flow of fuel thereto, means for causing simultane-

ous actuation of the valves, means for regulating the relative spacing of the valves, common means normally holding the valves in one position, and manual means for moving the valves to an operative position.

- 5 3. In a carbureter, a charge forming chamber, intake and exhaust ports therein, fuel supply means, a discharge nozzle communicating with the fuel supply means and received by the charge forming chamber, a valve chamber in the charge forming chamber around the intake port, a suction controlled valve slidable in said valve chamber, a valve slidable in the fuel supply means, means for adjustably and positively connecting the valves to cause synchronous movement thereof at all times, resilient means normally retaining the valves in closed positions, and manually operable 10 means engaged with the valves for operating the same independently of the suction operating means.

- 15 4. In a carbureter, a charge forming chamber, intake and exhaust ports therein, said intake and exhaust ports extending axially of the chamber and being disposed in alinement, fuel supply means disposed in alinement with the intake and exhaust ports, a discharge nozzle communicating 20 with the fuel supply means and received by the charge forming chamber spaced from the intake and exhaust ports, a valve chamber in the charge forming chamber around the intake port, said valve chamber having a 25 tapered opening, a suction controlled valve slidable in said valve chamber, a valve slid-

able in the fuel supply means and having positive connection with the suction controlled valve whereby the two will move in unison, means normally maintaining said 40 valves in closed positions, said means being common to both valves, and means for moving the valves to open positions manually.

5. In a carbureter, a charge forming chamber in the form of a casing having horizontally disposed intake and exhaust ports at its opposite ends, extending axially of the casing and located in alinement, a fuel supply conduit also extending axially of the casing in alinement with the intake port, 45 said conduit being provided with a downwardly curved discharge pipe extending into and longitudinally of the casing at the bottom portion thereof and having a flat perforated top wall, a valve chamber associated with the casing around the intake port and having a slot in its inner portion enlarging inwardly, a sleeve rotatable about the valve chamber and having a similar slot, means for rotating the sleeve, a suction controlled valve arranged within the valve chamber, a valve arranged in the conduit, means to cause simultaneous actuation of the valves on the suction stroke, means to cause simultaneous closing of the valves, and 50 means for regulating the positions of the valves independently of the two last mentioned means.

In testimony whereof, I affix my signature hereto.

HARRY E. TRAGER.
